(57) **CLAIM**

The ornamental design for a brush package, as shown and described.

DESCRIPTION

FIG. 1 is a perspective view as seen from the bottom, front and right side of a brush package showing our new design;

FIG. 2 is a front view thereof;

FIG. 3 is a rear view thereof;

FIG. 4 is right side elevational view thereof; and

FIG. 5 is a left side elevational view thereof;

FIG. 6 is a top view thereof; and,

FIG. 7 is a bottom view thereof.

The broken lines are included for the purpose of illustrating portions of the brush package that form no part of the claimed design.
